CLAIM

(60) Division of application No. 29/458,587, filed on Jun. 20, 2013, now Pat. No. Des. 761,840, which is a continuation-in-part of application No. 13/182,809, filed on Jul. 14, 2011, now Pat. No. 8,543,941, which is a division of application No. 13/171,130, filed on Jun. 28, 2011.

We claim the ornamental design for a display screen or portion thereof with an animated graphical user interface of a programmed computer system, as shown and described.

(51) **LOC (10) Cl. 14-04**
(52) **U.S. Cl.**

DESCRIPTION

USPC **D14/488**

FIG. 1 is a front view of the first image of a display screen or portion thereof with an animated graphic user interface of a programmed computer system;

(58) **Field of Classification Search**
USPC D14/485–95; D18/24–33; D19/6, 52;
D20/11; D21/324–33; 715/700–867,
715/973–77

FIG. 2 is a front view of a second image thereof;

CPC G06F 3/048–3/04897
See application file for complete search history.

FIG. 3 is a front view of a third image thereof;

FIG. 4 is a front view of a fourth image thereof; and,

FIG. 5 is a front view of a fifth image thereof.

(56) **References Cited**

The appearance of the image transitions sequentially between the images shown in FIGS. 1–5, respectively. The process or period in which an image transitions to another forms no part of the claimed design. The broken lines showing a display screen or portion thereof, lines and text form no part of the claimed design.
